D. BROWN.
COOLER.
APPLICATION FILED MAY 13, 1921.

Patented Mar. 21, 1922.

UNITED STATES PATENT OFFICE.

DAVIS BROWN, OF BUCYRUS, OHIO.

COOLER.

1,410,365.

Specification of Letters Patent. Patented Mar. 21, 1922.

Application filed May 13, 1921. Serial No. 469,341.

To all whom it may concern:

Be it known that I, DAVIS BROWN, a citizen of the United States of America, and resident of the city of Bucyrus, in the State of Ohio, United States of America, have invented certain new and useful Improvements in Coolers, of which the following is a specification.

This invention relates to improvements in coolers, particularly to those in which the cooling is effected through the evaporation of liquids such as water and which are designed for the cooling of milk, butter and the like, and the objects of the invention are to provide a simple and effective device of this character in which the supply of evaporable fluid may be maintained and distributed throughout the body of the cooler in such a way as to secure a maximum efficiency in operation.

More particular objects of the invention are to increase the porosity of the material from which the cooler is formed and to provide a special reservoir for the storage of the evaporable fluid.

Further objects still are generally to improve and simplify the construction of the device to enable it to more effectually perform the functions required of it.

It consists essentially of the improved construction hereinafter described in detail in the accompanying specification and drawings.

In the drawings:

Figure 1 is a perspective view of a cooler embodying my invention.

Figure 2 is a sectional elevation of the same.

Figure 3 is a plan view.

Figure 4 is a vertical sectional view.

Figure 5 is a horizontal cross section.

This application is a division of my earlier application, Serial No. 430,241, filed December 13, 1920.

In the drawings, like characters of reference indicate corresponding parts in all the figures.

Referring to the drawings:

A indicates the evaporating member or container formed of porous material and adapted to absorb an evaporable fluid such as water, and from its evaporation therefrom to thereby reduce the temperature of the contents of the container.

In the embodiments of the invention illus-

trated, the container is cylindrical in form, provided with an open bottom and shaped to conform to the shape of an ordinary milk bottle, the upper portion 10 of the container being frusto conical in shape and the outer side of the container being provided with a plurality of radially extending reinforced ribs 11. On the top of the container, a reservoir 12, cup-shape in form, is provided and adapted to contain the proportion of the water for evaporation.

The container is manufactured from porous material capable of absorbing water, but I prefer to construct it in the following manner: Suitable quantities of sawdust, cork dust, powdered coal and coke, or other suitable combustible material, preferably granular in form, mixed with clay and sufficient water added to form a stiff plastic mass, which is then molded to the desired form and shape, allowed to become dry and then burned in a suitable furnace in the manner well known in the art, until the combustible portions of the material are consumed, leaving in the place of the combustible substance a number of relatively small voids which increase the porosity of the container.

The container 10 is adapted to sit in a suitable saucer or pan B of any suitable material such as metal, wood or clay, which will also contain the evaporable fluid.

In using this form of the invention, for example, to cool a bottle of milk, a quantity of water is first placed in the saucer B and in the container 12. The milk bottle sits in the pan B, the evaporating member A is placed over it and preferably placed in the shade where there is a current of air, which will increase the rate of evaporation. The water in the pan B and reservoir 12 should be renewed from time to time as it is absorbed by the pores in the wall of the container A.

When it is desired to cool butter or other articles not themselves contained in a water proof container, the article should be placed on a suitable block which will raise them above the water line of the water in the pan B.

It will be observed that the radially extending reinforced ribs 11 unite at the top and bottom in flanges 11^a and 11^b which extend around the container.

As many changes could be made in the

above construction and many widely different embodiments of my invention within the scope of the claims, constructed without departing from the spirit or scope thereof, 5 it is intended that all matter contained in the accompanying specification and drawings shall be interpreted as illustrative and not in a limiting sense.

What I claim as my invention is:

- 10 1. A cooler of the character described comprising an evaporating porous container formed with a lower cylindrical portion and an upper frusto conical portion having a plurality of radially extending reinforcing

ribs, and annular flanges at the top and bottom connected to the ribs. 15

2. A cooler of the character described comprising an evaporating porous container frusto conical in form having radially extending reinforcing ribs, and annular flanges 20 united to the ribs at the top and bottom.

In witness whereof I have hereunto set my hand in the presence of two witnesses.

DAVIS BROWN.

Witnesses:

MARGARET WILLACKER,
H. E. STARTSMAN.
